UNITED STATES PATENT OFFICE

152,555

DESIGN FOR A DISPLAY CASE

Glen E. Millard, St. Paul, Minn.

Application March 13, 1947, Serial No. 137,585

Term of patent 3½ years

(Cl. D80—5)

To all whom it may concern:

Be it known that I, Glen E. Millard, a citizen of the United States, residing at St. Paul, county of Ramsey, and State of Minnesota, have invented a new, original, and ornamental Design for Display Case, of which the following is a specification, reference being had to the accompanying drawing, forming part thereof:

I claim:

The ornamental design for a display case, as shown.

GLEN E. MILLARD.
